Primary Examiner — Eric Goodman*Assistant Examiner* — John Reickel(74) *Attorney, Agent, or Firm* — Smartpat PLC; Axel Nix(57) **CLAIM**

I claim the ornamental design for a light source with coupling adaptor for an ice tip, as shown and described.

DESCRIPTION

FIG. 1 is a perspective view of a light source with coupling adaptor for an ice tip showing my new design;

FIG. 2 is a perspective view thereof, showing my design in use;

FIG. 3 is a left side view thereof, the right side view, top view, and bottom view being identical;

FIG. 4 is a front view thereof; and,

FIG. 5 is a rear view thereof.

The broken line showing of an ice tip in FIG. 2 is for the purpose of illustrating environmental structure and forms no part of the claimed design.
